M. E. ERICKSON & A. W. MOGREN.

SAFETY EXTINGUISHER FOR LAMPS.

APPLICATION FILED MAR. 21, 1914.

1,120,043.

Patented Dec. 8, 1914.

UNITED STATES PATENT OFFICE.

MELVIN E. ERICKSON AND ARTHUR W. MOGREN, OF GRANTSBURG, WISCONSIN.

SAFETY-EXTINGUISHER FOR LAMPS.

1,120,043.

Specification of Letters Patent.

Patented Dec. 8, 1914.

Application filed March 21, 1914. Serial No. 826,385.

To all whom it may concern:

Be it known that we, MELVIN E. ERICKSON and ARTHUR W. MOGREN, citizens of the United States, residing at Grantsburg, in the county of Burnett and State of Wisconsin, have invented certain new and useful Improvements in Safety-Extinguishers for Lamps, of which the following is a specification.

10 This invention relates to new and useful improvements in safety attachments for oil burning lamps.

The principal object of my invention is to provide a snuffer or extinguisher which will automatically operate to extinguish the flame of the lamp wick in case the lamp is tampered with or accidentally overturned.

A further object is to so construct the extinguishing device that it will move into operative position immediately upon the displacement of the lamp base from its normal position on the table or other supporting structure, unless the lamp is to be moved from one place to another and the person carrying the lamp holds the extinguisher in inoperative position by grasping a finger lug which is carried by the actuating rod of the extinguisher.

The above and additional objects are accomplished by such means as are illustrated in the accompanying drawings, described in the following specification, and then more particularly pointed out in the claims which are appended hereto and form a part of this application.

With reference to the drawings, wherein there has been illustrated the preferred embodiment of this invention as it is reduced to practice, and throughout the several views 40 of which similar reference numerals designate corresponding parts, Figure 1 is a vertical section taken through a lamp equipped with our automatic safety extinguishing device; and Fig. 2 is a detail perspective view 45 showing the main elements of the extinguishing attachment.

Before taking up the description of the details of construction of our invention, it is desirable to explain that while the device 50 has been illustrated as applied to a particular form of oil burning lamp, and will be hereinafter described in that connection, the principles of the invention may be applied to any type of oil burning lamp by subjecting the device to a few minor and obvious 55 mechanical changes.

In the drawings, the numeral 10 designates as an entirety the oil container or body portion of a standard form of lamp. The container 10 is carried in the usual manner 60 on a hollow base or casing 11, having a reduced upper terminal 12 of any suitable design. A burner, indicated at 13, is threaded in the neck 14 of the container 10 in the well known manner.

The extinguisher or snuffer consists preferably in a sheet metal sleeve 15 which is mounted for sliding movement on the upper terminal of the wick tube 16, and is normally held in position below the exposed 70 portion of the wick by means to be herein-after described. As hereinbefore explained, the extinguishing device is so designed that it will operate automatically to snuff out the flame of a wick 17 whenever the base 11 is 75 displaced from its normal position on a table or other supporting structure. As a means for accomplishing this result, there is provided an actuating rod 18 which is riveted or otherwise secured at its upper terminal 80 to the sleeve 15, as indicated at 19. This actuating rod 18 is mounted for sliding movement through a tube 20, which extends through the oil container 10 of the lamp, as clearly shown in Fig. 1. This tube 20 extends diagonally through the container so that the lower terminal of the rod 18, indicated at 21, is considerably offset with respect to the vertical center line of the base 11.

Arranged exteriorly of the base member 90 is a cup-shaped member or pan 22, which is also formed of sheet metal, and is preferably circular in shape, being of considerable area so that it will engage flatly against the 95 top of a table, and will not be likely to mar or scratch the surface thereto. Extending vertically from the member 22 and eccentrically with respect thereto is an arm 23, which is pivotally connected to the lower 100 terminal of the actuating rod by means of a rock arm or lever 24 and a link rod 25.

The member 24 is pivotally connected at one terminal by a pin 26 to the upper terminal of the member 23, while its other terminal is pivotally connected by a pin 27 to the lower terminal of the member 25. As a means for supporting the member 24, there is provided a dependent arm 28 which is secured at its upper terminal to a partitioning 110 plate 29 inserted in the lower end of the member 12. It will be seen upon reference

to Fig. 1 that the member 24 is pivoted adjacent its terminal 27 to the lower end of the arm 28 by a pivot pin 30.

The link rod 25 extends through an opening 31 formed in the base member 11, and is threaded at its upper terminal, whereby it may be engaged with a coupling sleeve 32, the upper end of which receives the terminal 21 of the actuating rod 18. A set-screw 33 is threaded into the coupling sleeve, and engages the member 10 for holding it against withdrawal. The head of the set-screw 33 is formed in the nature of a cylindrical extension, which serves as a finger grip whereby the operator may hold the extinguishing sleeve 15 in inoperative position when the lamp is moved from one table to another, as will be hereinafter fully explained.

From a central point of the member 22 extends a vertical sleeve 34. This member 34 receives a vertical downwardly extending centering rod 35, the upper terminal of which is soldered or otherwise secured to the member 10, as indicated at 36. A helical spring, indicated at 37, surrounds the tubular sleeve 34, and the rod 35, and has its upper terminal secured to the partitioning plate 29 and its lower terminal secured to the outwardly extending flange 38, which is formed on the lower terminal of the member 34. This spring 37 is of the expansive type, and normally serves to hold the pan 22 exteriorly of the hollow base casing 11.

The actual construction and arrangement 35 of the several parts of this invention being thus described, it now remains to explain the manner in which the sleeve 15 is automatically actuated to extinguish the flame of the lamp wick simultaneously with the displacement of the base member 11 from its normal position on a table or other supporting structure on which the lamp has been placed.

It will be seen in Fig. 1 that when the lamp is placed on a table, the pan 22 lies in the plane of the lower edge of the base member 11, and that when the pan is in this position the terminal 27 of the member 24 is depressed to such a point that the sleeve 15 is held with its upper edge below the upper edge of the wick tube 16 through the medium of the connecting rod 18. It will be seen that the pan 22 will be projected beyond the confines or limits of the base member 11 by means of the sleeve 37 in the event 55 that the lamp is lifted from the table or is over-turned, causing the base to be displaced. The projection of the pan 22 from beyond the limits of the base member 11 will, of course, swing the member 24 on its pivot 30, causing 60 the member 25 to move upwardly through the opening 31, resultantly causing the sleeve 15 to be slid upwardly on the wick tube 16 by means of the actuating or connecting rod 18. When the sleeve 15 is thus 65 slid upwardly on the member 16, it incases

the projecting terminal of the lamp wick, and, of course, extinguishes the flame by cutting off the supply of air necessary to support combustion.

In case the user of the lamp wishes to 70 move the lamp from one place to another without extinguishing the flame, the sleeve 15 may be held in inoperative position by holding the member 37 with the fore-finger or thumb as may be most convenient. It 75 will be obvious that should the person carrying the lamp accidentally drop it, the sleeve 15 will be immediately projected into 80 operative position by the sleeve 37, and further that should a child unfamiliar with the igniting device attempt to lift the lamp from its proper place, the extinguishing device will immediately move into operative position.

In reduction to practice, it has been found that the form of this invention illustrated in the drawings, and referred to in the above description as the preferred embodiment, is the most efficient and practical; yet realizing that the conditions concurrent with the 90 adoption of this device will necessarily vary, it is desirable to emphasize the fact that various minor changes in details of construction, proportion and arrangement of parts 95 may be resorted to, when required, without sacrificing any of the advantages of this invention, as defined in the appended claims.

What we claim is:—

1. The combination with an oil burning lamp including a wick tube, an oil reservoir, 100 and a hollow base member, of an extinguishing device including a sleeve member slid-able on the wick tube, an actuating rod connected to the sleeve and movable through the oil container, a pan arranged in the base member, yieldable means normally tending to project the pan beyond the confines of the base, and pivoted means opera-105 tively connected to the pan and adjustably connected to the actuating rod, whereby the rod will be moved upwardly, causing the sleeve to incase the projecting terminal of the wick simultaneously with the projection of the pan beyond the confines of the base.

2. The combination with an oil burning 110 lamp, of a flame extinguishing device in-cluding a sleeve engaging against and slid-able upon the wick tube of the lamp burner, and means for automatically projecting the sleeve upwardly to incase the projecting ter-115 minal of the lamp wick, upon the displace-ment of the lamp base from its support, said means including a rod connected at its upper terminal to the sleeve and mounted for slid-ing movement through the lamp body, a 120 supporting arm arranged in the base of the lamp, a crank pivoted intermediate its length to the supporting arm, a link rod piv-125 otally connected to one terminal of the crank and adjustably connected to the lower ter-130

5 minal of the said rod, a pan member pivotally connected to the crank at the terminal thereof remote from the link rod, a sleeve rising centrally from the pan, a guide rod vertically arranged in the lamp base and having its lower terminal slidably received within the tube and a spring wound about the tube and bearing against the pan for normally projecting the pan beyond the limits of the lamp base.

10 3. In combination with an oil burning lamp including a wick tube, an oil reservoir and a hollow base member, of an extinguishing device including a sleeve embracing the wick tube and mounted for sliding movement thereon, an actuating rod connected to the sleeve and movable through the reservoir, the lower terminal of the rod being disposed exteriorly of the lamp, a pan member arranged in the base of the lamp, yieldable means normally tending to project the member beyond the confines of the base, a link rod adjustably connected to the lower terminal of the actuating rod and pivoted 15 means operably connecting the link rod and said pan member whereby the rod will be moved upwardly causing the sleeve to incase the projecting terminal of the wick simultaneously with the movement of the pan member beyond the confines of the base.

20 4. The combination with an oil burning lamp having a wick tube, an oil reservoir, and a hollow base member, of an extinguishing device including a sleeve member slid- 25 able upon the wick tube and embracing the same, an actuating rod connected to the sleeve at its upper terminal and mounted for sliding movement through the reservoir,

the lower terminal of the actuating rod being disposed exteriorly of the reservoir, a 40 pan arranged in the base of the lamp, means freely connecting the pan to the lower terminal of the actuating rod, and yieldable means normally tending to project the pan beyond the confines of the base. 45

5. The combination with an oil burning lamp, of a flame extinguishing device including a sleeve slidably mounted on the wick tube of the lamp burner, and means for automatically projecting the sleeve upwardly to incase the projecting terminal of the lamp wick upon the displacement of the lamp base from its support, said means including an actuating rod connected at its upper terminal to the sleeve and mounted 50 for sliding movement through the lamp body, said rod having its lower terminal disposed exteriorly of the lamp body and at a point between the lamp body and the lamp base, a spring-pressed pan mounted in the 55 lamp base, a crank pivoted in the lamp base and connected to the pan, a link rod pivoted to the crank and mounted for sliding movement through the wall of the base, and a removable member adjustably and detachably connecting the link rod and the first-mentioned rod, said member being disposed exteriorly of the lamp. 60 65

In testimony whereof we affix our signatures in presence of two witnesses.
